UNITED STATES PATENT OFFICE.

FRANK H. ARMSTRONG, OF AUBURN, NEW YORK, ASSIGNOR TO CORONA TYPEWRITER COMPANY, INC., OF GROTON, NEW YORK, A CORPORATION OF NEW YORK.

TYPEWRITING-MACHINE.

1,375,344.

Specification of Letters Patent. Patented Apr. 19, 1921.

Application filed October 16, 1917, Serial No. 196,867. Renewed September 24, 1919. Serial No. 325,962.

To all whom it may concern:

Be it known that I, FRANK H. ARMSTRONG, a citizen of the United States of America, and a resident of Auburn, county of Cayuga, 5 State of New York, have invented certain new and useful Improvements in Typewriting-Machines, of which the following is a full and clear specification.

This invention has particular reference to 10 the means for supporting and guiding the platen carriage, and the object of the invention is to provide simple means whereby the carriage will be assured of an easy, steady movement, devices being provided 15 for compensating for wear and for slight unevenness of the anti-friction ball raceways, as more fully hereinafter set forth.

Referring to the annexed drawings—

Figure 1 is a rear elevation of a carriage 20 and its support;

Fig. 2 is a bottom view thereof;

Fig. 3 is an end elevation thereof partly, in section, taken on the line 3—3 of Fig. 1;

Fig. 4 is a fragmentary transverse section 25 through the race-way having the movable flange or member;

Fig. 5 is a horizontal section on the line 5—5 of Fig. 3;

Fig. 6 is a vertical longitudinal sectional 30 view on the line 6—6 of Fig. 5;

Figs. 7 and 8 are side elevations of two slightly different forms of ball spacers; and

Fig. 9 is a detail view showing a modification 35 of the stop for the yieldable race-way.

Referring to the drawing by reference characters, it will be observed that the carriage consists of a sheet metal plate *a* whose ends are bent up at *b* to form supports for 40 the platen *c* and whose longitudinal edges are bent downwardly the full length of the plate *a* to form a pair of depending flanges *d*, these flanges being formed with longitudinal race-way channels *e*, which face inwardly, that is, toward each other.

The supporting or base plate *f* is affixed to the frame bars 10 of the carriage frame and is provided with longitudinally extending upwardly flanges *g* bent to form outwardly facing ball channels *h*, *h'*, these channels *h*, *h'* being complementary to the outer channels *e* so that the anti-friction balls *i* are received between each pair of channels. One of the

flanges *g* is formed integral with the base-plate *f* and the other is pivotally connected thereto and has a limited inward and outward swing. This movable flange is normally pressed outwardly by a pair of springs *j*, each consisting of a flat plate fastened to the under side of the base-plate *f* and having its free end extending up through an opening therein and bearing against the convex side of the channel *h* in the adjacent movable flange *g*, to thereby press said movable flange outwardly and maintain the balls at both sides of the carriage in operative position and compensate for unevenness in the tracks as well as for wear. To further compensate for unevenness in the track due to imperfection of manufacture, or presence of grit, or slight twisting or distortion of the track members, I divide the swinging member or flange into two parts, 55 division being made at *k*, about midway the ends of the swinging track member, one of the springs *j* being arranged to bear against each of the sections of the track member.

Two balls are arranged in each race-way, one at each side of mid-length of the carriage, by means of a spacing bar *l*, this bar 60 extending across break *k* in the movable track-member *g* and serving to restrict the travel of each ball in the race-way to one section of the divided track member or flange. To prevent an excessive movement 65 of this anti-friction device in either direction, I provide stop-screws *m* in the race-ways. Each of the spacing bars *l*, is provided with a head *i'* at each end, in which is formed a central aperture for the reception of one of the balls *i*. For lightness, the bar *l* is made narrower than the race-way grooves, and when thus employing a narrow bar it is essential to provide means for preventing the bar tilting edgewise 70 far enough to permit the rings or heads *i'*, to jam between the balls and the race-way channels, this jamming tendency being particularly evident when sufficient downward or lateral pressure is exerted upon the platen-carrying plate to swing the movable race-way flange *g* away from its companion race-way flange *d*.

To prevent this abnormal tilting of the bar, I provide each of the heads *i'* with a pair of projections *i''* which 75 extend respectively upwardly and down- 80 85 90 95 100 105

wardly far enough beyond the race-way grooves to strike against the adjacent flat faces of the flanges *d* and *g* and thus serve to maintain the spacing bar approximately 5 edgewise vertical under all conditions. This non-jamming spacing member or bar will be particularly advantageous in use on a Corona machine, in view of the fact that in that machine the platen-carrying member 10 of the carriage is frequently subjected to downward and lateral thrusts in folding and unfolding the platen carriage frame, the bars 10 of which are shown in the drawings. To prevent excessive swinging inwardly 15 of the movable race-way flange, I provide a series of set screws *n* tapped upwardly through the supporting plate *f* and so positioned as to form stops against which the channel portion *h* of the flange strikes in 20 case the flange is forced an undue distance inwardly. A lock nut *o* is provided on each of the set screws for locking it in its adjusted position. Instead of set screws, I may, as shown in Fig. 9, form a non-adjustable stop *n*¹¹, by striking up a portion of 25 the body of the base plate *f*. These channel-flange stops are particularly advantageous in that they prevent the movable channel member from being swung inwardly 30 far enough to permit the platen-carrying member being disconnected from the base member of the carriage. These arresting stops are particularly advantageous in a machine of the Corona type in which the 35 platen-carrying member, in the act of folding and unfolding the machine, is exceedingly liable to be subjected to transverse thrusts.

The sections of the movable flange *g* 40 formed with the race-way *h* are pivotally connected to the base-plate *f* by having each of the sections provided at each end with a hook lug *o'* extending through the base plate and engaging the under side of the 45 plate. The hook lug *o'* at the outer end of each of the sections engages in a notch *p* formed in the end of the base-plate and the hook lug *o'* at the inner end of each section extends through one of the spaced longitudinal slots *q* formed in the plate *f*, the slots *q* being long enough to permit the hooks *o'* to pass therethrough. In assembling, the hook lug *o'* at the inner end of each section 50 is inserted through the adjacent slot *q* and then the section is moved longitudinally until the shank of the outer hook lug engages in notch *p*. The free ends of both hook lugs on each section will then engage the under side of the base-plate. When 55 each section is assembled on the base-plate in this manner, the two ends thereof meet at the joint *k*, and the two sections are locked in this assembled relation by means of a plate *r* fastened to the under side of the base 60 or supporting plate *f* by screws *s* and pro- 65 vided with lugs *t* engaging behind the two center lugs *o'*. The two sections are thus held against outward sliding action, with their hook-shaped ends engaging under the base-plate *f*. The slots *p* and *q* are sufficiently wide, compared with the thickness of the plates from which the sections of the movable race-way flange are formed, to permit a limited swinging movement of the sections, the movement of each section being independent of the other section. The rear longitudinal edge of the base plate *f* is bent upwardly to form a longitudinal flange *u* to stiffen the plate. 70

It will be observed that the race-way flanges *g* carried by the base plate *f* are formed with flat upper edge portions extended to near the under face of the platen-carrying plate *a*. This not only aids in stiffening the flanges on the base plate, thus 75 permitting them to be constructed of thin-gage sheet metal, but also permits these flanges *g* to function as stops in case the platen-carrying plate *a* is forced downwardly with sufficient severity to cause the 80 movable race-way *h* to be swung inwardly far enough to permit the said plate *a* to strike against the upper edges of said flanges *g*. This stop function of the flanges *g* is particularly advantageous in folding machines, such as the Corona, in which pressure on the platen-carrying member causes the flanges to have a cam-like action, thus 85 tending to swing the movable race-way flange away from its companion or complementary flange and displace the balls. This same tendency to cam the flanges apart and displace the balls occurs when the carriage of the Corona machine is lifted and thrown 90 backwardly into operative position, as well 95 as when the carriage is swung forwardly and dropped down into compact position. 100

The nature and scope of the invention having been thus indicated and its preferred embodiment having been specifically described, what is claimed as new is:

1. In combination, a platen carriage and a support therefor, the carriage and the support being provided with co-operating race-way flanges, one of the flanges being movable and means being provided for normally pressing it toward its companion flange, said movable flange being composed of independently-movable sections, for the purpose set forth. 115
2. In combination, a platen-carrying member provided with a pair of race-way flanges, a supporting member likewise provided with a pair of race-way flanges, anti-friction balls in the race-ways formed by said flanges and means for spacing the balls so as to maintain them at opposite sides of a point mid-length of the platen-carrying member, one of said race-way flanges being divided into 120 two parts both parts being pivotally con-

1. Connected to one of said members, and means for normally pressing said sectional race-way flange against the balls, for the purpose set forth.
5. 3. In combination, a platen-carriage member having race-way flanges, a supporting member having complementary race-way flanges, one of said flanges having a limited pivotal movement on one of said members, 10 and stops arranged on this latter member to engage the movable race-way flange to prevent undue movement thereof.
15. 4. The combination with two sheet metal members one adapted to support a platen and the other adapted to be attached to the frame of the machine and each being provided with a pair of race-way flanges, the flange on one of the members being movable toward and from its companion race-way 20 flange, of springs fastened to the member carrying said movable race-way flange and bearing normally against the flange to force it toward its companion race-way flange.
25. 5. In combination, a pair of sheet metal members one being adapted to support the platen and the other being adapted for attachment to the typewriting machine and each provided with a pair of race-way flanges, one of the flanges on one of the members being movable toward and from its companion flange, this movable flange being sectional and the connection between each section and its supporting member consisting of hook-shaped lugs engaging in openings in said member, means being provided for holding these lugs in locked position.
30. 6. In combination, a platen-carriage plate, a base-plate, race-way flanges carried by said plates, one of said flanges being pivotally connected to one of said plates and being sectional, the connection between each section and the plate consisting of a pair of hook-shaped lugs extending through openings in the plate and engaging the opposite 35 side thereof, and a locking device on the plate.
35. 7. A platen supporting structure, comprising a traveling carriage having raceway channels, a sheet metal carriage bed having a rigid integral flange at one edge formed with a raceway channel and a longitudinal stiffening flange at its opposite edge, a race-way member divided into independently movable sections each having a rocking connection at one edge with the bed adjacent said stiffening flange and formed with a raceway channel, anti-friction rolling elements in the raceways formed by said channels, and means for yieldably pressing the 40 sections of said divided member against the anti-friction elements.
45. 8. A platen-supporting structure, comprising a sheet metal traveling carriage having depending raceway flanges, a sheet metal carriage bed having an upstanding integral raceway flange at one edge and a detachable raceway channel member adjacent its opposite edge having a rocking connection with the base of the bed, the integral bed flange and said raceway channel member being 50 inclosed within the flanges on the carriage and having upwardly extending vertical portions above the raceway channels the upper edges of which lie closely adjacent the under side of the carriage, anti-friction rolling elements in the raceways, and means for yieldably forcing the rocking raceway member toward its companion raceway flange on the carriage.
55. 9. A platen-supporting structure, comprising a sheet metal traveling carriage having depending raceway flanges, a sheet metal carriage bed having an upstanding integral raceway flange at one edge and a detachable raceway channel member adjacent its opposite edge having a rocking connection with the base of the bed, the integral bed flange and said raceway channel member being 60 inclosed within the flanges on the carriage and having upwardly extending vertical portions above the raceway channels the upper edges of which lie closely adjacent the under side of the carriage, anti-friction rolling elements in the raceways, and means for yieldably forcing the rocking raceway member toward its companion raceway flange on the carriage.
65. 10. In combination, a plate member adapted to support a platen and provided with depending race-way flanges, a base-plate provided with upstanding race-way flanges, one of said race-way flanges being 65 attached to its carrying plate by hook-lugs entering openings in said plate.
70. 11. In a typewriting machine, the combination of a support, platen-carrying means, and an anti-friction bearing interposed between the support and platen-carrying means comprising two race-ways and a plurality of rolling elements confined in said race-ways, one member of one of said race-ways being divided into independently 75 yieldable sections along each of which one rolling element is adapted to travel.
75. 12. In a typewriting machine, the combination of a support, platen-carrying means, and an anti-friction bearing interposed between the support and platen-carrying means comprising two race-ways and groups of opposed rolling elements confined in said race-ways, one member of one race-way being divided into independently 80 yieldable sections with each of which one group of opposed rolling elements coöperate.
80. 13. In a typewriting machine, the combination of a platen carriage, a support for the carriage, and an anti-friction bearing 85

interposed between the carriage and its support comprising two race-ways, one member of one race-way being divided into independently yieldable sections, a plurality of opposed rolling elements confined in said race-ways, each rolling element in the race-way having the divided member being adapted to travel along a single section of the divided member.

10 14. The combination of a pair of sheet metal members, one of which is adapted to support a platen and the other of which is adapted for connection with the frame of a typewriting machine, each of said members being provided with a pair of race-way flanges adapted to coöperate with the flanges on the other member, one flange on one member being divided into sections which are independently movable toward and from 15 the coöperating flange, interlocking rocking connections between each section of the divided flange and its supporting member, independent means for normally pressing each section of the divided flange toward its coöperating flange, and rolling elements confined in the race-ways formed by said flanges.

15. The combination of a sheet metal platen carriage formed with integral depending race-way flanges, a sheet metal base plate provided with race-way flanges extending upwardly within the depending flanges on the carriage, one of the flanges on the base plate having an interlocking 20 30 35 40 45 50 55 60 65 70 75 80 85 90 95 100 105 110 115 120 125 130 135 140 145 150 155 160 165 170 175 180 - tions having rocking connections with their supporting member, means for yieldably forcing the sections of the divided flange toward its coöperating flange, a pair of balls in each raceway, a spacing bar in each raceway having eyes adjacent each end thereof to receive the balls, and lugs adjacent each end of the spacing bars traveling between the flat faces of the flanges.
- 10 22. A platen support, comprising a sheet metal traveling member having raceway flanges, a sheet metal stationary member having raceway flanges, all of said flanges having flat faces at opposite sides of the raceway channels and one of said flanges being divided midway its length into sections having rocking connections with their supporting member, means for yieldably forcing the sections of the divided flange toward its coöperating flange, a pair of balls in each raceway, a spacing bar in each raceway having eyes adjacent each end thereof to receive the balls, and lugs adjacent each end of the spacing bars traveling between the flat faces of the flanges, and stops carried by the flanges on the stationary member adjacent each end thereof adapted to engage the balls, said stops and the spacing bars coöperating to limit the travel of each ball to one side of mid-length of the stationary member.
- 25 23. In combination, a platen-carriage member having race-way flanges, a supporting member having complementary race-way flanges, one of said flanges having a yielding movement on its carrying-member, and a stop to prevent undue movement of the movable flange away from its complementary flange.
- 30 24. In a typewriting machine carriage, a sheet metal base member provided with up-standing race-way flanges, a sheet metal platen-carrying member provided with depending race-way flanges, rolling elements in the race-ways formed by said flanges, the flanges on one member extending above the ball race-ways and close to the opposing face of the other member to form stops to limit the downward movement of the platen-
- 35 carrying member, one of said flanges being laterally yieldable toward and from its companion race-way flange.
- 40 25. The combination of a platen carriage having raceway channels, a pair of stationary raceway members having channels co-operating with the channels on the carriage, one of said members being divided into independently movable sections, means for yieldably forcing said sections of the divided member toward its companion race-way channel, rolling elements in the raceways, spacing devices for the rolling elements in the raceways, and means for limiting the travel of the spaced balls.
- 45 26. In combination, a platen carriage member having race-way flanges, a supporting member having complementary race-way flanges, one of said flanges having a limited movement on its carrying-member, and a stop on this latter member arranged to engage the movable flange to prevent undue movement thereof away from its complementary flange.
- 50 27. In a typewriting machine carriage, a base member provided with upstanding flanges having race-way channels, a platen-carrying plate lying over the top edges of said flanges and provided with depending race-way flanges, rolling elements in said race-ways, said upstanding flanges extending to near the under face of said platen-carrying plate, one of said flanges being laterally yieldable toward and from its companion race-way flange.
- 55 28. In a typewriting machine carriage, a plate member adapted to support a platen and provided with depending race-way flanges, a base plate provided with up-standing race-way flanges, one of said race-way flanges being attached to its carrying plate by hook-lugs entering openings in said plate, and a locking plate engaging said hook-lugs and detachably locking said race-way flange to said plate.
- 60 This specification signed this tenth day of October, A. D. 1917.
